UNITED STATES PATENT OFFICE.

DONALD M. BLISS, OF WEST ORANGE, NEW JERSEY.

SOUND-REPRODUCER AND DIAPHRAGM THEREFOR.

1,284,222.

Specification of Letters Patent. Patented Nov. 12, 1918.

Application filed March 30, 1917. Serial No. 158,530.

To all whom it may concern:

Be it known that I, DONALD M. BLISS, a citizen of the Dominion of Canada, residing at West Orange, in the county of Essex and State of New Jersey, have invented certain new and useful Improvements in Sound-
Reproducers and Diaphragms Therefor, of which the following is a specification.

My invention relates to phonograph or sound reproducers and especially to improved diaphragms therefor and the manner in which the same are mounted in the sound-box. My preferred diaphragm comprises a supporting member of flexible material and of high tensile strength, preferably of thin woven fabric, such as finely woven silk, which is secured in the casing of the sound-box while stretched nearly to its elastic limit, the predetermined tension to which this member is subjected being evidenced by the fact that the same has a predetermined tone or pitch when vibrated. A stiffening disk of less diameter than the supporting member is secured thereto, this disk having a comparatively large central opening therethrough substantially in alignment with the neck of the reproducer. This disk is preferably formed of cellular material such as compressed paper and is physically stiff relatively to the tensioned supporting member. A thin disk of high density, relative to that of the stiffening disk just referred to, is secured to the diaphragm to cover the central opening therein. This central disk is preferably cupped or concave and the stylus lever is attached thereto. I have found it difficult to maintain a uniform tension in the supporting member of the diaphragm when the latter is supported by rings secured to opposite faces of the material. This is because there is a tendency for the supporting rings to collapse at certain points, unless they are made unusually heavy and rigid. Accordingly, I prefer to secure the supporting member of the diaphragm between a dished plate, which comprises part of the casing of the sound-box, and a ring. Also, preferably, screws are passed through the plate, diaphragm member and ring and a shell or cover is fitted over the casing, so as to completely cover all of the screw-heads and the edges of the plate and ring, thereby preventing accidental disturbance of the tension of the diaphragm by tampering with the screws.

The above being a brief description of my preferred device, it should be understood that my invention is not limited thereto and also that my invention comprises certain sub-combinations in addition to the main combination of elements. The theoretical considerations on which my invention is based will be more fully disclosed hereinafter. It may, however, be briefly noted at this point that the effect of the tensioned and light supporting member of the diaphragm, together with the stiffening member secured thereto, is to provide both a "tension stiffness" and a physical stiffness to produce a structure which is both resilient and light. Also, by providing in a diaphragm a relatively thick and light member such as the stiffening disk referred to, having a central opening or sound chamber therein, over which is secured a thin member of high density, to which the stylus lever is connected, various advantages accrue. Briefly, the overtones and the higher frequency vibrations are well reproduced by the thin central member of high density, these vibrations not being distributed to any considerable extent in the mass of the larger member to which the thin dense disk is secured. At the same time, the size and inertia of the main portion of the diaphragm results in the faithful reproduction of tones of lower pitch in proper balance.

The features just referred to provide a diaphragm construction having a center of high density attached to a surrounding area of low sound conductivity. The result of this combination is to prevent the free transmission of sound vibrations from the center of the diaphragm to its periphery, and this I consider a distinct advantage. Sound vibrations produced in the central disk tend to be reflected back to their originating point from the junction of the central disk with the surrounding material of low sound conductivity, because of the very different character of the conducting medium beyond the junction from that of the medium in which such vibrations originate. Accordingly, it seems to be the case that the high frequency vibrations which produce the so-called "scratch" in reproducing from a sound record do not travel beyond the central metal or other high density disk, but are reflected back from the junction of the metal disk with the rest

of the diaphragm and so are not distributed through the diaphragm as a whole, but are largely suppressed. At the same time overtones and soprano notes, etc., which are of an amplitude considerably greater than the "scratch" vibrations will be reproduced by the central disk which vibrates practically by itself in reproducing the same.

In order that a clearer understanding of my invention may be had, attention is hereby directed to the accompanying drawings forming part of this application and illustrating a preferred embodiment of my invention. In the drawings, Figure 1 represents a bottom plan view of a sound reproducer, Fig. 2 is a section taken on line 2—2 of Fig. 1 and Fig. 3 is a sectional view of the diaphragm shown in Fig. 2 taken on line 2—2 of Fig. 1.

Referring to the drawings, the casing 1 of the sound-box is formed as a metallic disk, somewhat concaved or dished, and having a plane annular surface 2 adjacent its periphery. The diaphragm, of which the supporting member is shown at 3, is secured between the surface 2 of plate 1 and a clamping ring 4.

The diaphragm, in its preferred form as explained, comprises, in addition to the supporting member 3, a stiffening member or members, shown in the drawing at 5 and 6, and a central member 7 of relatively high density to which is attached the stylus lever 8. This lever carries a stylus 9 and is pivoted in any usual manner as on centers carried by the lugs 10.

The supporting member 3 is formed of flexible material of high tensile strength and is preferably a disk of finely woven silk, or other woven fabric of high tensile strength. In the production of the diaphragm and reproducer, according to my preferred method, this fabric is first stretched to about one-half of its elastic limit. This member is maintained under tension through the various operations. Next, the stiffening disk 5 is cemented to the stretched fabric, this disk having an axial opening 11 therethrough. The member 5 is formed of some material of low sound conductivity, preferably of light character, and of considerable physical stiffness in comparison with the supporting member 3. It may be formed of cork,

wood, fiber, or other suitable materials, but is preferably formed of compressed paper. It is of considerable thickness relative to members 3 and 7. I have illustrated a means of obtaining the desired thickness which comprises cementing a similar disk 6 to the disk 5, disk 6 being of smaller diameter than disk 5. This disk 6 has a relatively large central opening 12 therethrough which may be in substantial alinement with the neck 13 of the reproducer. Members 5

and 6 form, in effect, a single stiffening member having a large central opening or sound chamber formed therein.

The member 7 comprises a small thin disk of relatively dense material and high resilience in comparison with members 5 and 6. The preferred material is resilient metal. This member is preferably arched, as shown, to increase its stiffness and resilience. It is secured to the member 5 to cover the central opening through the diaphragm, preferably by cementing an annular disk 14, which may be formed of strong paper, over the marginal flange of member 7 and to the supporting member 3.

After the metal member 7 has been cemented in place, the diaphragm is then given a coating of finishing varnish which makes the same air-tight. Member 3 is then given a further stretching, nearly to its elastic limit, and while in this stretched condition it is secured to the reproducer. Member 3 is secured between ring 4 and the edge portion of plate 1 preferably by cement and additionally by screws 15 having heads 16 on the outer side of plate 1. In practice, the final stretching of member 3 is accurately determined by comparing the tone or pitch of the member when vibrated with a standard pitch, the middle C, for example, and stretching member 3 until its tone is brought into accordance with the predetermined pitch.

If desired, a dampener may be employed to prevent excessive vibration of member 7. This may take the form, for example, of an annulus 17 of felt or other suitable material interposed between the member 3 and the member 7 adjacent to the periphery of the concave portion of the latter.

The diaphragm may, of course, be secured between rings in the usual fashion, if desired, but I have found that it is difficult to maintain a uniform tension with such rings after the diaphragm has been cut loose from the stretching frame, as there is a tendency for the rings to collapse at certain points. To avoid making the rings impractically heavy, therefore, I find it preferable to use in place of one of the rings the arched plate 1 as described, which acts as a closure and sound reflecting surface for the sound-box and provides a clamping member which will not buckle.

It is, of course, important that the tension of the diaphragm should not be altered after it has been adjusted, and, therefore, means should be provided for preventing an irresponsible person taking the construction apart. My preferred construction comprises a shell or cover 18 which fits over the back of plate 1, completely covers the heads 16 of the screws and extends around the edges of plate 1 and ring 4, as shown at 19. This casing 18 may be held in position by being clamped

and secured under the flanges of the neck or nipple 13, which serves for connecting the reproducer to a tone arm of a phonograph or the like. This casing prevents an instrument being inserted between the edges of the plate and ring, protects the heads of the screws and gives a finished appearance to the reproducer.

The reproducer described gives an exceptional quality of reproduction which may be attributed partly to one and partly to another sub-combination of the elements described as comprising my preferred construction. The use of the diaphragm members 3 and 5, or 3, 5 and 6 provides a construction in which stiffness is produced partly by the physical stiffness of members 5 and 6 and partly by what I may term the "tension stiffness" of the member 3. The efficiency of a reproducer, other things being equal, depends largely upon the lightness, stiffness and resilience of its diaphragm. Such usual diaphragm materials as mica, fiber, or the like, have a low tensile strength and are brittle or heavy. With the structure described, however, the total resilience or elasticity is greater than that which would be produced by either the stiffening member or the supporting member alone, while the stiffening member provides a sufficient inertia and permits the use of a sufficiently large diaphragm to reproduce tones of varying pitch in proper balance.

Considering the combination of the stiffening member with the central member 7, it should be noted that soprano, or other tones of high frequency, will vibrate the small central diaphragm practically without any dissipation in or through the heavier diaphragm of different density, while vibrations of deeper tone and greater energy will vibrate the diaphragms as a whole. In reproducers as usually made, the mass and low resilience of the diaphragm prevents the same from following the stylus lever accurately, a large percentage of the higher frequencies of sound vibration not being well reproduced. On the other hand, if the diaphragm is made smaller in diameter and lighter in weight, the production of the higher frequency has been improved, but the proper balance between different voices, for example in the case of a musical record, will be lost.

Also, as stated, I have found that a diaphragm, formed as described by me, produces much less scratch or surface noise than if the diaphragm were composed of a homogeneous material. It seems to be an advantage to so construct the diaphragm as to prevent the free transmission of sound vibrations from the center of the diaphragm to its periphery. Sound vibrations are largely reflected back to their originating point if they meet a conducting medium or

widely different character from that in which they originate. It seems likely that the high frequency vibrations which produce the so-called "scratch" do not travel beyond the central metal disk, in the construction described, but are reflected back from the junction of the metal disk with the rest of the diaphragm and are largely suppressed. It will, therefore, be evident that one feature of my invention consists in providing a diaphragm having concentric areas of widely varying sound conductivity, for junction of such areas forming sound reflection rings for impeding the transmission of the vibrations to the outer edge of the diaphragm.

It will be evident that my invention is not limited to the exact details of the construction described, but is as broad as is indicated by the accompanying claims.

What I claim is:—

1. In a sound-box, a compound diaphragm comprising a relatively thick and light member having a central opening therethrough, supporting member having an alined opening, and a thin member of high density, relative to that of the first, secured to a face of one of said first members to cover the opening therethrough, substantially as set forth.

2. In a sound-box, a diaphragm including a member having a central opening therethrough, and being formed of cellular material, relatively light and thick, a supporting member and a third diaphragm member secured to one of said other members, to cover said opening, said second member being relatively thin and of high density, substantially as set forth.

3. In a sound-box, a diaphragm having portions formed of different materials, said portions being arranged concentrically one outside the other, and being of widely varying sound conductivity, the central portion being of higher density and sound conductivity relative to the surrounding portion, substantially as set forth.

4. In a sound-box, a compound diaphragm comprising a member having a central opening therethrough, a supporting member therefor, and a third diaphragm member secured to one of said other members, to cover said opening, said first member being of greater mass and lower sound conductivity than the third, and said third member being of resilient metal, substantially as set forth.

5. In a sound-box, a compound diaphragm comprising a member having a central opening therethrough, a supporting member therefor and a third diaphragm member secured to one of said other members, to cover said opening, said first member being of greater mass and lower sound conductivity than the third, and said third member being cupped or arched and of a relatively high

density and resiliency, substantially as set forth.

6. In a sound-box, a compound diaphragm comprising a thin flexible supporting member of high tensile strength and elasticity, a physically stiff disk member of less diameter than the supporting member, secured thereto, said disk member and supporting member each having a central opening therethrough, and a thin disk of relatively high density secured to one of said members to cover the said opening, substantially as set forth.

7. In a sound-box, the combination of a casing, a diaphragm comprising a supporting member of flexible material of high tensile strength, and a physically stiff member of less diameter secured thereto, means for securing said supporting member in the casing under tension, and means for preventing alteration of such tension after the parts have been adjusted, substantially as set forth.

8. In a sound reproducer, the combination of a hollow plate, a clamping ring, a diaphragm secured and supported between

the edge portion of said plate and said ring, clamping screws extending through the edge portion of said plate and through said diaphragm into said ring, and a casing extending over the outer surface of said plate, inclosing the heads of said screws, and bent to extend around the peripheral edges of the plate and ring, substantially as set forth.

9. In a sound reproducer, the combination of a pair of clamping members, a diaphragm secured and supported adjacent its edge between said clamping members, clamping screws extending through one of said members and through said diaphragm into the other of said members, and a casing extending over the top surface of the reproducer, inclosing the heads of said screws, and bent to extend around the peripheral edges of said pair of clamping members, substantially as set forth.

This specification signed and witnessed this 28th day of March, 1917.

DONALD M. BLISS.
